[57] CLAIM

The ornamental design for eyeglass components, as shown and described.

DESCRIPTION

FIG. 1 is a front perspective view of the eyeglass components of the present invention;

FIG. 2 is a front elevational view thereof;

FIG. 3 is a rear elevational view thereof;

FIG. 4 is a right side elevational view thereof, the left side elevational view being a mirror image thereof;

FIG. 5 is a top plan view thereof;

FIG. 6 is a bottom plan view thereof;

FIG. 7 is a front perspective view of an alternative embodiment of the eyeglass components of the present invention;

FIG. 8 is a front elevational view of the eyeglass components of FIG. 7;

FIG. 9 is a rear elevational view of the eyeglass components of FIG. 7;

FIG. 10 is a right side elevational view of the eyeglass components of FIG. 7, the left side elevational view being a mirror image thereof;

FIG. 11 is a top plan view of the eyeglass components of FIG. 7; and,

FIG. 12 is a bottom plan view of the eyeglass components of FIG. 7.

The phantom lining shown in FIG. 7 illustrates environmental structure.
